UNITED STATES PATENT OFFICE.

THOMAS SPENCER MILLER, OF SOUTH ORANGE, AND JOSEPH H. DICKINSON, OF MONTCLAIR, NEW JERSEY.

CABLE TENSION APPARATUS.

No. 839,019.

Specification of Letters Patent.

Patented Dec. 18, 1906.

Application filed June 23, 1906. Serial No. 323,013.

To all whom it may concern:

Be it known that we, THOMAS SPENCER MILLER, a resident of South Orange, and JOSEPH H. DICKINSON, a resident of Montclair, in the county of Essex and State of New Jersey, citizens of the United States, have invented certain new and useful Improvements in Cable Tension Apparatus, of which the following is a specification.

10 This invention relates to tension apparatus, and has particular application to a novel and useful type of tension apparatus adapted to be employed in connection with cables and cableways.

15 The invention consists in the construction, combination, and arrangement of parts set forth in and falling within the scope of the appended claims.

20 In hoisting apparatus of the class commonly known as "cableways" the load is usually carried by means of a carriage moving along a rope or ropes forming part of a system. It frequently happens that the load placed upon the carriage is more than the 25 trackway along which the carriage runs is able to sustain, and the consequence is that such rope or ropes forming the trackway are liable to be broken, and thus cause the dismantling of the apparatus and the interruption 30 of the work. Especially is this the case in cableways employed in logging operations, and in the present instance and in the annexed drawings we have shown merely by way of illustration our apparatus used in 35 connection with a cableway-skidder for hauling logs. It is our intention to provide a type of engine designed to have connected thereto and operated thereby a rope or cable, such engine, in addition to any other function it 40 might perform, being also capable of maintaining a certain tension upon a rope or cable, so that in case the load or strain on the cable should become too great instead of such cable snapping or breaking the drum tension 45 will be automatically released and the cable will yield or give a sufficient degree.

50 In the accompanying drawings, Figure 1 is a view in side elevation of a portion of a cableway, showing our invention applied thereto. Fig. 2 is a top plan view of an engine embracing our improvements, certain well-known portions of the engine being omitted.

Referring now to Fig. 1, 5 indicates the head or spar tree. 6 is the main cable along

which the carriage 7 travels. 8 is the out-haul rope for hauling the carriage outward along the cable. 9 indicates the in-haul and the slack-pulling rope, while 10 is the hauling-rope carrying the gripping-tongs 11. The outhaul rope 8 passes over a sheave 12 and is operated by the engine-drum 13 of the engine A. 14 and 15 are blocks for the in-haul or slack-pulling rope 9, driven from the drum 16 of the engine. The main cableway 6, which in the present instance is shown as 65 provided with a continuation or extension 6^a, passes over a sheave-block 17, carried by the head-tree, and such extension is provided with the running tension device 18, formed by the block members 19 and the tension-rope 20, reeved therethrough. 21 is a loop for anchoring the main cable to a stump or other anchorage 23. Now in the present instance it is the main cable, here comprising the cable 6 and its extension 6^a, that it is desired to tension; and, as has been described, the running connection 18 forms a tension device, and the tension placed upon the cable 75 may be regulated by operating the rope 20 from the engine. This is done as follows: 80 The engine A is provided with the usual frame, steam-cylinders, and other parts, which are too well known to require description, and is also provided with a power-shaft 24, carrying the pinion-wheel 25, intermeshing 85 with the large gear-wheel 26 upon the shaft of the loading-drums 27, so that the drum-shaft is thus operated. This power-shaft 24 also carries clutches embodying a pinion clutch member 28, loosely mounted thereon, 90 and the clutch member 29, keyed to revolve with said shaft and to slide along the same to be thrown into and out of clutching engagement with the pinion member 28 in a manner well understood. Loose pinion-clutch members 28 mesh in turn with the large gear-wheels 30 of the tension-drums 31 on the shaft 32. Each drum is of the friction type—that is to say, the large gear-wheel 30 is mounted upon one drum part 33, 100 adapted to turn with the shaft, while the spool portion 34 of the drum is loose upon the shaft and has a friction-surface adapted to move into frictional engagement with the drum part 33. A suitable friction setting-device 35 is also provided having a setting-pin 36, designed to press against one part of the loose drum-section 34 and move the 105

same into its frictional engagement. A circular rack 37 is arranged adjacent to the large gear 30 on each drum. A pawl 38 co-acts with said rack to hold the same in engagement therewith and prevent the drum-section 33, with its large gear, from turning at certain times. The tension-rope 20 is designed to be wrapped about one of the drums 31 and to be operated thereby. In Fig. 2 we have shown two such drums 31, the reason for this being that in cableways, such as shown in Fig. 1, there may be employed two or more tension devices for main cable, so that the raising and lowering of the latter and the changing of the cables may proceed without any great interruption; but it is to be understood that, if necessary, we may employ but one of the tension-drums 31. The above is a description of the construction of the engine, and we will now proceed to describe its function and operation.

Let it be supposed that the main cable is to be erected to withstand a strain of forty thousand pounds. The drum-section 34, around which the cable is wrapped, is moved into frictional engagement with the drum-section 33 by means of setting device 35 and is set so that the frictional engagement between the two surfaces will not hold and the section 31 will slip against the section 33 at any strain over forty thousand pounds. The clutch 29 is then thrown into operative engagement with the pinion-clutch member 28 and the engine started to wind the tension-rope 20. When the rope has been properly tensioned, the clutch member 29 is thrown into its inoperative position and the pawl or dog 38 moved to lock in the ratchet-wheel 37, and thus hold the drum 31 against revolution, the two sections 34 and 33 being interlocked by the friction. Now so long as the load upon the carriage is under forty thousand pounds in the example given the two drum-sections 34 and 33 will continue to be frictionally interlocked; but should the load—for instance, the log—go over forty thousand pounds, and thus place an abnormal strain upon the main cableway, the friction-face of the drum-section 34 will slip relative to the section 33, and the load will thus tend to drag or pull the cable toward the ground, owing to the slipping or turning of the drum-section 34. When the tension has sufficiently slackened, so that the strain upon the cable does not amount to more than forty thousand pounds, again the slipping of the section 34 will cease, and the friction will again take hold. In some instances under very heavy load the main cable would probably be dragged or pulled downward until it reached the ground; but there would be no snapping or breaking of the same, owing to the tension release just described. This is a great saving, not only as concerns the breaking of the cable itself, but the time and labor

necessarily expended in replacing the dismantled parts of the apparatus and again rigging the same.

It will of course be understood that the friction may be set to withstand any strain commensurate with conditions, and, furthermore, that the invention is not limited in its application and in the specific features of construction herein enumerated; but we wish it to be understood that it may be used for divers purposes, and that modification and variation in the structural features may be made without departing from the spirit of the invention or scope of the claims.

What we claim is—

1. The combination of a support, a cable, a tension-line for said cable, and means operating said tension-line to maintain a predetermined tension on the cable under a certain load and to release the tension on the cable when the load thereon exceeds a certain limit.

2. The combination with a support, a cable, tension means therefor, and means controlling the tension means to maintain a predetermined tension on the cable up to a certain limit of strain and to release the tension on the cable when such limit of strain is exceeded.

3. The combination of a support, a cable, a tension-line connected to said cable, a drum part about which said tension-line is wrapped a second drum part adapted to be moved into and out of contact with the first drum part and adapted to be moved relative thereto when in contact to release the tension on the cable when the strain or load on the cable exceeds a predetermined limit.

4. The combination with a cable, of means for tensioning the same comprising an engine having two drum parts, means for shifting said drum parts into and out of frictional engagement, and means for maintaining one of said parts against revolution when in contact with the other drum part and permitting the last-mentioned part to slip relative to the stationary drum part when the strain or load upon the cable exceeds a predetermined limit.

5. The combination of a cable, a drum part, means for locking said part against rotation, a second drum part carrying the cable and adapted to be shifted into and out of frictional contact with the first-mentioned drum, and to slip or shift relative to the first drum part when the strain on the cable exceeds a predetermined limit.

6. The combination of two drum parts, means for locking one of said drum parts against movement, and means for shifting the other drum part into frictional engagement so that the friction contact will be maintained up to a certain strain but such drums will slip at a strain beyond that predetermined limit.

7. The combination with a cable or rope, means for tensioning the same comprising an engine having a plurality of drum parts, means for shifting said parts into frictional engagement to interlock the drums and maintain a desired tension upon the rope under a predetermined strain, and means for permitting said drums to slip relative to each other to release the tension when the strain upon the cable exceeds a certain limit.

8. The combination of a support, a main cable, a tension-line connected to the main cable, a drum part about which said tension-line is wrapped, a second drum part adapted to be shifted into and out of contact with the first drum part, means for locking one of said drum parts against movement to maintain a desired tension upon the tension-line, when the drums are interlocked, such drums slipping relative to each other when the strain upon the cable exceeds a predetermined limit.

9. The combination of a support, a main cable passing over a guide on the support, a tension-line connected to the main cable, a

running-block for said line, a drum member for operating the tension-line, a second drum member adapted to be shifted into interlocking frictional engagement with the first-mentioned drum member to interlock therewith and maintain a desired tension upon the tension-line and cable, said drum parts slipping relative to each other when the strain upon the cable exceeds a predetermined limit.

10. The combination of a cable, means for supporting the same, and means for maintaining said cable at a desired tension under a predetermined strain or load, and releasing the tension upon said cable when the strain or load thereon exceeds the predetermined limit.

In testimony whereof we have signed our names to this specification in the presence of two subscribing witnesses.
